(57) **CLAIM**

The ornamental design for a kitchen and grill food handling and preparation hand tool, as shown and described.

DESCRIPTION

FIG. 1 is a top perspective view of a kitchen and grill food handling and preparation hand tool showing my new design; FIG. 2 is a front elevational view thereof; FIG. 3 is a left side elevational view thereof; FIG. 4 is a rear elevational view thereof; FIG. 5 is right side elevational view thereof; FIG. 6 is a top plan view thereof; and, FIG. 7 is a bottom plan view therefor.

My kitchen and grill food handling and preparation hand tool is characterized by its solid construction, curved form fitting hand grip handle and the angle design of the fork type tines on the front of the tool.
